Fig. 7

Fig. 6

Fig. 8

The diagram shows a cross-section of a rectangular water tank. The tank is supported by four vertical legs (1) at the corners. The interior is divided into two main sections by a central vertical wall. The upper section contains water up to a dashed line, with a horizontal line labeled 52 above it. The lower section contains water up to a dashed line, with a horizontal line labeled 51 below it. The left vertical leg is labeled 56 at the top, 53 in the middle, and 54 at the bottom. The right vertical leg is labeled 55 at the top, 56 in the middle, 50 at the bottom, and 54 at the very bottom. The base of the tank is shown as a hatched line.

UNITED STATES PATENT OFFICE

2,396,818

GENERATOR TYPE HEATER

James L. Breese, Santa Fe, N. Mex., assignor to
Oil Devices, Santa Fe, N. Mex., a limited partnership of Illinois

Application July 2, 1943, Serial No. 493,251

8 Claims. (Cl. 126—95)

My invention relates to an improvement in generator type heater and has for one purpose to provide a burner which is light, simple and efficient.

Another purpose is to provide a burner structure adapted for use in the field, for example with military stoves.

Another purpose is to provide improved means for maintaining the fuel supply cool.

Another purpose is to provide improved means for insulating the fuel supply from an adjacent zone of mixing and combustion.

Another purpose is to provide means for controlling the rate of combustion by controlling the supply of air to the body of liquid fuel from which a gaseous fuel is generated.

Other purposes will appear from time to time throughout the specification and claims.

My invention is illustrated more or less diagrammatically in the accompanying drawings, 20 wherein:

Figure 1 is a side elevation with parts in vertical section;

Figure 2 is a plan view with parts broken away;

Figure 3 is a section along the line 3—3 of Figure 1;

Figure 4 is a section on an enlarged scale along the line 4—4 of Figure 1;

Figure 5 is a similar section illustrating the parts in a different position;

Figure 6 is a vertical section through a variant form of the device;

Figure 7 is a section along the line 7—7 of Figure 6;

Figure 8 is a section along the line 8—8 of Figure 6.

Like parts are indicated by like characters throughout the specification and drawings.

Referring first to Figures 1 to 5 of the drawings, 1 indicates any suitable supporting surface which, in the field, may be the ground. Mounted upon the supporting surface is a stove structure including a base 2, a lower portion or chamber member 3, an upper portion or chamber member 4, a flue 5 and an intermediate partition 6, centrally apertured as at 7. It will be understood, however, that the burners may be used with a variety of stoves or heaters, the one illustrated herein being a practical example.

8 generally indicates a tank or storage zone for liquid fuel. It includes a bottom 9, a top 10, a circumferential generally cylindrical, inner wall 11, a circumferential outer wall 12, and a plurality of radial spacing partitions 13. It will be observed that the wall 12 terminates at its lower edge somewhat above the wall 11 in order to provide space for air to pass upwardly through the passages between the adjacent radial partitions 13. These partitions may also serve as

cooling fins. 14 is a filling neck normally closed by a removable cap 15. 16 is an air inlet tube normally fixed upon the top member 10. It is shown as extending practically to the bottom of the tank. It is provided with opposite air outlet slots 17 and 18, the slot 18 being of substantially greater width than the slot 17. The slots are shown as extending below the level of the liquid so that within the possible variations of the liquid level, air will always be able to pass out through the slots 17 or 18 at or adjacent the level of the liquid.

Radially within the tube 16 is an inner tube 19, which may be controlled by a handle 20 herein shown as resting upon the upper end of the tube 16, which serves as a positioning abutment. The inner tube 19 has a plurality of slots 21, 22 which are herein shown as of about the same width. It will be observed that the effective cross sectional area for the admission of air can be varied by using the handle 20 to rotate the tube 19 in relation to the tube 16. In the position shown in Figure 4, the inner slots 21 and 22 are both unmasked. In the position of Figure 5, the slot 21 has been masked but the slot 22 is still unmasked. A further rotation of the inner tube in the direction of the arrow in Figure 5, can be employed partially or entirely to close the slot 22. Thus the air supplied to the fuel in the tank 8 can be controlled manually from outside from substantially zero flow to a predetermined maximum. It will be understood, of course, that the proportions and shapes of the slots may be widely varied or other systems of apertures may be employed, but the structure shown herein has been proven efficient in practice.

Extending upwardly from the top 10 of the tank 8 is a vapor outlet 25 which terminates in a horizontal portion 26, which in turn communicates with the interior of a pot generally indicated as 27 and herein shown as horizontally axised. The pot is provided with a plurality of air inlets 28 located at various distances from the bottom or end 29 of the pot. 30 is a baffle centrally apertured as at 31. Beyond the baffle is shown a plurality of air inlets 32 of greater diameter and more closely spaced than the apertures or inlets 28. The top or end of the pot is closed by a flame ring 33 with a central aperture 34 aligned with a tube 35 which extends through an aperture in the wall of the stove element 3. This may, for example, be a fire door closed by any suitable closure 36. The parts are preferably proportioned so that the member 35 may be inserted in the fire door 36 for a snug fit as shown in Figure 2. The parts may readily be inserted into and removed from each other.

Surrounding the pot 27 is a closed housing 40, 60 herein shown as generally cylindrical and as hav-

ing a bottom or end 41 provided with an aperture 42 through which the element 25 extends. This aperture is preferably substantially larger in diameter than the diameter of the member 25 so that air can flow inwardly therethrough to supply the apertures 28 and 32.

It will be noted that the wall 11 extends above the plane of the top 10 of the tank and forms with an upturned flange 10a of the tank top 10, a space into which cooling water may be poured, if desired.

In the operation of a generator burner of the type herein shown, combustion is initiated in the container 8, which may for example be filled fairly full as shown in Figure 1. The handle 20 is set to provide a sufficient supply of air through the slots 21 and 22 to support combustion. The combustion taking place near the outlet 25 vaporizes a substantial quantity of the liquid fuel. The fuel vaporized by the partial combustion maintained by the inflowing air flows through the outlet 25, 26 into the interior of the pot 27. There the vaporized fuel receives additional air through the apertures 28. These apertures provide primary air for the vaporized fuel. The primary mixture then flows through the aperture 31 of baffle plate 30 and receives enough secondary air through the apertures 32 for complete combustion of the vaporized hydrocarbon. The flame in practice flows through the inlet 35 into the lower stove chamber 3, through the aperture 7, and into the upper stove chamber 4. It will be understood that the rate of combustion, and the amount of fuel vaporized and burned, is controlled by varying the volume or rate of flow of air admitted through the tubes 16 and 19 and the slots 21 and 22.

Referring to Figures 6 to 8 inclusive, a similar generator type burner is illustrated. However the tank 50 is shown having a bottom 51, a top 52, end portions or walls 53 and side walls 54. An outer wall structure 55 is shown connected by spacing and heat exchange vanes 56, the wall 55 being spaced upwardly at its lower edge to permit a flow of air upwardly between the walls 53 and 54 and the outer wall 55. The air which flows upwardly in this fashion passes into a space housed by a top cover 57. It will be observed that the outer wall 55 extends endwise beyond the fuel tank and is secured to the flame ring structure 58. The top cover 57 may be secured to the same flame ring structure. The bottom of the space thus defined is closed by an additional wall 59. Thus the air which passes upwardly about the tank to cool it is in communication with the space about the pot 27a, as shown in Figures 6 and 7 and may pass through the apertures 28a and 31a of that pot. It will be understood that the two pots are substantially identical and the pot will therefore not be further described.

In order to deliver the products of combustion and the vaporized fuel from the tank to the pot, I illustrate a T-member 60, a side branch 61 connected by a pipe 62 with the interior of the pot 27a. 63 illustrates a nut secured to the bottom 51 of the tank. Screw threaded into it is the bottom of the air tube 64. The top of this tube carries a cup 65 which may be welded thereto and which extends somewhat above the top of the tube. The cup 65 is seated in the top of the T 60, which is counterbored to receive it. The cup serves as means to hold the T 60 firmly down against the top 52 of the tank. It will be observed that the

tube 64 is provided with air inlet slots 66, 66a, which may be identical with the slots 17 and 18.

67 is an inner air inlet tube corresponding to the tube 19, of Figure 1. It is provided with slots 68 and 69 which may be identical with the slots 21 and 22 of Figures 4 and 5. It may also be provided with a handle 70.

In the operation of the device as shown in Figures 6 and 7, the cup 65 may be employed to receive a priming volume of fuel. When the priming charge is positioned and ignited, a flow of air down through the tube draws the burning material down to the surface of the fuel in the tank. The control of the air for the burner operates just as in the case of Figures 1 and following, the volume or rate of flow of air being employed to control the rate of vaporization and rate of combustion.

The form of Figures 6 and 7 is particularly efficient in that the tank is insulated from the burner by air intervals through which cooling air flows on its way to the space about the pot 27a.

It will be understood also that the air admission and lighting equipment shown in Figures 6 and 7 may be employed equally well with the form of Figures 1 and following.

It will be understood that the inner air tube 67 or 19 rests by gravity in the position in which it is shown in the drawings, the handle serving as the limit means. Not only is the inner tube readily rotatable in relation to the outer, but it can readily be upwardly withdrawn by its handle as when the cup 65 is employed to receive a priming charge. At the starting stage, the priming charge

is lighted and flows freely down through the outer tube and to the surface of the fuel in the tank. At the starting stage, an excess supply of air is advantageous, so the shutting effect of the inner tube is not necessary. When ignition has been begun, the inner tube can then be dropped back in position and employed to meter the air supply.

It will be realized that while I have shown and described in my drawings an operative device, still many changes might be made in the size, shape, number, arrangement and disposition of the parts without departing materially from the spirit of my invention. I wish, therefore that my showing be taken as in a large sense diagrammatic rather than illustrative.

I claim:

1. In combination, in a heater and burner structure, a fuel storage and vaporizing tank adapted to contain a substantial supply of a liquid fuel, a hydroxylating burner pot having a closed end and an open end and a circumferential wall provided with a plurality of air inlet apertures at various distances from its ends, a flame ring partially closing the open end and having a generally central aperture, a vapor duct extending from the tank through the closed bottom of the pot, a heater, means for maintaining the interior of the heater in communication with the interior of the pot, means for delivering air to the tank above the level of the fuel therein, at a variable rate of flow, for thereby controlling the rate of vaporizing combustion in said tank and of combustion in said pot.

2. In combination, in a heater and burner structure, a fuel storage and vaporizing tank adapted to contain a substantial supply of a liquid fuel, a hydroxylating burner pot having a closed end and an open end and a circumferential wall provided with a plurality of air inlet apertures at various distances from its ends, a flame ring partially closing the open end and having a generally central aperture, a vapor duct extending from the

tank through the closed bottom of the pot, a heater, means for maintaining the interior of the heater in communication with the interior of the pot, means for delivering air to the tank above the level of the fuel therein, at a variable rate of flow, for thereby controlling the rate of vaporizing combustion in said tank, and of combustion in said pot, and means for directing additional air to the space about said pot, for passage through the air inlets of the pot wall.

3. In combination, in a heater and burner structure, a fuel storage and vaporizing tank adapted to contain a substantial supply of a liquid fuel, a hydroxylating burner pot having a closed end and an open end and a circumferential wall provided with a plurality of air inlet apertures at various distances from its ends, a flame ring partially closing the open end and having a generally central aperture, a vapor duct extending from the tank through the closed bottom of the pot, a heater, means for maintaining the interior of the heater in communication with the interior of the pot, means for delivering air to the tank above the level of the fuel therein, at a variable rate of flow, for thereby controlling the rate of vaporizing combustion in said tank, and of combustion in said pot, and means for directing additional air to the space about said pot, for passage through the air inlets of the pot wall, including an air directing housing surrounding the tank, adapted to cool said tank and to protect it from the heat of combustion in the burner.

4. In combination, in a heater and burner structure, a fuel storage and vaporizing tank adapted to contain a substantial supply of a liquid fuel, a hydroxylating burner pot having a circumferential generally cylindrical wall, with a horizontal axis, and a closed end and an open end, said wall being provided with a plurality of air inlet apertures at various distances from its ends, a flame ring partially closing the open end, and having a generally central aperture, a duct extending from the tank through the closed bottom of the pot, a heater, means for maintaining the interior of the heater in communication with the interior of the pot, means for delivering air to the tank above the level of the fuel therein, at a variable rate of flow and to thereby control the rate of vaporizing combustion in said tank.

5. In combination, in a heater and burner structure, a fuel storage and vaporizing tank adapted to contain a substantial supply of a liquid fuel, a hydroxylating burner pot having a circumferential generally cylindrical wall, with a horizontal axis, and a closed end and an open end, said wall being provided with a plurality of air inlet apertures at various distances from its ends, a flame ring partially closing the open end, and having a generally central aperture, a vapor duct extending from the tank through the closed bottom of the pot, a heater, means for maintaining the interior of the heater in communication with the interior of the pot, means for delivering air to the tank above the level of the fuel therein at a variable rate of flow and to thereby control the rate of vaporizing combustion in said tank, and an air directing housing surrounding said tank and said pot, spaced outwardly from the walls of said tank and pot and provided with air inlets through which air may pass to the interior of the housing.

6. In combination, in a heater and burner structure, a fuel storage and vaporizing tank adapted to contain a substantial supply of a liquid fuel, a hydroxylating burner pot having a circumferential generally cylindrical wall, with a horizontal axis, and a closed end and an open end, said wall being provided with a plurality of air inlet apertures at various distances from its ends, a flame ring partially closing the open end, and having a generally central aperture, a vapor duct extending from the tank through the closed bottom of the pot, a heater, means for maintaining the interior of the heater in communication with the interior of the pot, means for delivering air to the tank above the level of the fuel therein, at a variable rate of flow and to thereby control the rate of vaporizing combustion in said tank, and an air directing housing surrounding said tank and said pot, spaced outwardly from the walls of said tank and pot and provided with air inlets through which air may pass to the interior of the housing, the means for delivering air to the tank and for varying the rate of flow of air to the tank extending outwardly through the wall of said air directing housing.

7. In combination, in a heater and burner structure, a fuel storage and vaporizing tank adapted to contain a substantial supply of a liquid fuel, a hydroxylating burner pot having a closed end and an open end, a circumferential wall provided with a plurality of air inlet apertures at various distances from its ends, and a generally centrally apertured flame ring partially closing the open end, said pot being horizontally axised and being spaced laterally from the tank, a vapor duct extending from the tank through the closed bottom of the pot, a heater, means for maintaining the interior of the heater in communication with the interior of the pot, positioned laterally of the pot beyond the open end of the pot, and means for delivering a varying rate of flow of air to the tank, and to thereby control the rate of vaporizing combustion in said tank and of combustion in said pot.

8. In combination, in a heater and burner structure, a fuel storage and vaporizing tank adapted to contain a substantial supply of a liquid fuel, a hydroxylating burner pot having a closed end and an open end, a circumferential wall provided with a plurality of air inlet apertures at various distances from its ends, and a generally centrally apertured flame ring partially closing the open end, said pot being horizontally axised and being spaced laterally from the tank, a vapor duct extending from the tank through the closed bottom of the pot, a heater, means for maintaining the interior of the heater in communication with the interior of the pot, positioned laterally of the pot beyond the open end of the pot, means for delivering a varying rate of flow of air to the tank, and to thereby control the rate of vaporizing combustion in said tank and of combustion in said pot, and a surrounding housing extending about the pot and the tank and spaced from the side walls of the tank, having air inlets about the bottom of the side walls of the tank adapted to permit a flow of air through the interior of said housing substantially throughout the periphery of the tank.

JAMES L. BREESE.
